UNITED STATES PATENT OFFICE.

ANSON WOLCOTT, OF WOLCOTT, INDIANA.

FREIGHT-CAR.

SPECIFICATION forming part of Letters Patent No. 326,701, dated September 22, 1885.

Application filed June 20, 1885. (No model.)

To all whom it may concern:

Be it known that I, ANSON WOLCOTT, of Wolcott, in the county of White and State of Indiana, have invented certain new and useful 5 Improvements in Freight-Cars; and I do hereby declare that the following is a full, clear, and exact description thereof, reference being had to the accompanying drawings, and to the letters of reference marked thereon, which 10 form a part of this specification.

This invention relates to improvements in fastening devices for the hinged sides of freight-cars; and it consists in the matters hereinafter described, and pointed out in the appended 15 claims.

The invention may be more fully understood by reference to the accompanying drawings, in which—

Figure 1 is a side elevation of a closed or 20 "box" car embodying my invention. Fig. 2 is a transverse section of the same, taken upon line $x-x$ of Fig. 1. Fig. 3 is a fragmentary side view of a flat car, showing one end thereof. Fig. 4 is a detail sectional view of the 25 parts shown in Fig. 3, taken upon line $x-x$ of said figure. Fig. 5 is a detail section taken upon line $y-y$ of Fig. 3. Fig. 6 shows a side door constructed to slide vertically.

In the said drawings, A indicates a car-body 30 of any usual or preferred construction, and B are hinged wall sections or flaps, which are connected at their upper margins by hinged or pivotal connections b with the car-frame or suitable supports thereon, and are adapted to 35 open outward to permit the free discharge of the contents of the car.

In Fig. 1 a box-car is shown, having its stationary side walls, A', extended to within, say, a foot and a half or two feet of the floor there- 40 of, and provided with wall-sections B B, hinged at their upper edges to the said stationary walls, and arranged to close the longitudinal opening or passage between the lower margins of the stationary walls A' A' and the 45 car-floor.

The hinged parts B B, in the case of a box-car, may embrace the entire thickness of the car-wall, or it may include the outer sheathing or planking only. The latter construction 50 is shown in the drawings, in which the frame-pieces of the car-walls are shown as extended downwardly and attached to the longitudinal

side frame-pieces of the car in the usual manner, and the outer planking or sheathing, a, is fastened at its lower edge to a longitudinal beam, A², located at the lower edge of the wall A', and affording attachment for the pivotal connections or hinges b of the flaps B. The latter may be framed or constructed in any desired or preferred manner, a simple 60 and convenient form thereof being herein shown, in which they consist of longitudinal planks attached to vertical metal bars b', pivoted at their upper ends in castings a' upon the car-wall to form the hinges b, and extended at their lower ends beyond the edges of the flaps, whereby they may be conveniently engaged with the locking devices for holding the flaps closed. The said bars are desirably located upon the outer faces of the flaps, which 70 are arranged to come, when closed, practically flush with the car-wall and with the outer surface of the longitudinal side pieces of the car.

C is a metal bar extending along the side 75 of the car adjacent to the lower edge of the flap B, and constructed to slide longitudinally in suitable bearings upon said frame. In the particular construction shown the said bar extends from end to end of the car, and is located in a longitudinal groove in the frame-piece A³ thereof, with its outer surface flush with the outer face of the frame-piece, and is held in said groove by plates a², secured over the groove and bar. Upon the said bar C, at 85 points adjacent to the lower ends of the bars b', are located outwardly-bent metal pieces or plates c, which are separated from the bar sufficiently, Fig. 5, to permit the lower ends of the bar b' to enter behind them, and which 90 are made of notched form, as clearly shown in Figs. 1, 3, and 5, whereby they may be conveniently secured to the bar C at two points of attachment.

The bar C is connected with suitable de- 95 vices whereby it may be moved a distance equal to or somewhat greater than the width of the bars b', and the plates c are so arranged that when the said bar C is thus moved the said plates will be shifted over the ends of the 100 bars b, and will thereby lock and hold the lower edge of the flaps B from outward movement.

Any suitable means may be used for actu-

ating the bar E, that therein shown consisting of a lever, D, pivoted upon the side piece, A', and connected with the bar C by a link, d, said lever being preferably arranged to engage a segment, D', provided with notches adapted to hold the lever in position, either with the locking devices closed or open.

5 In order to prevent the flaps or sides from being opened by unauthorized persons, a padlock, d', or other locking device may be applied to secure the lever in position with the plates c in engagement with the bars b.

10 A means for sustaining the hinged side of a flat car is shown in Figs. 3 and 4. In this case the hinged sides or flaps B are pivotally connected at their upper ends with posts or standards E, fixed in the car-platform adjacent to the inner faces of the flaps. The sides or flaps B are in this case constructed with vertical 15 bars b' in the same manner as before described, and the posts E are provided upon their upper ends with castings e, provided with lugs or ears, affording bearings for the pivots of the hinges b of the flaps.

20 25 The means for locking the flaps shown in the figures last mentioned are similar to those before described.

The box-car shown is provided with the usual central doorway at the middle of each of its sides, 30 and the flaps B are constructed to extend from points at either side of the doorway to the ends of the car, a low or half door, F, such as is usually used in grain-cars, being shown as in place within the doorway to retain the load.

35 35 In Fig. 2 the car is shown in dotted lines as inclined or tilted sidewise, so as to discharge the load by the opening of the flaps B, as will

occur when the car is used in connection with the dump device shown in a prior application, Serial No. 163,735, filed by me upon the 28th 40 day of April, 1885.

I claim as my invention—

1. The combination, with a car, of hinged flaps B and means for securing the flaps, consisting of metal bars, as b', projecting from the free edges of the flaps, and a longitudinally-movable bar upon the car-body, provided with projecting parts constructed to engage said bars b', substantially as described.

2. The combination, with a car, of hinged flaps B, provided with metal bars, as b', projecting from the free edges of the flaps, and a longitudinally-movable bar, C, provided with parts c, adapted to engage the end portions of the bars b', and means for shifting said bar 50 longitudinally, substantially as described.

3. The combination, with a car and hinged flaps B, of fastening devices comprising bars b', projecting from the free edges of the flaps, a longitudinally-movable bar, C, provided with 55 projecting parts constructed to engage the bars b', and a locking device for securing said bar from longitudinal movement when the flaps are closed and fastened, whereby access to the car by unauthorized persons may be prevented, substantially as described.

In testimony that I claim the foregoing as my invention I affix my signature in presence of two witnesses.

ANSON WOLCOTT.
